UNITED STATES PATENT OFFICE.

WILLIAM W. CROCKER, OF SOMERVILLE, MASSACHUSETTS.

METALLIC WINDOW.

1,405,817.

Specification of Letters Patent.

Patented Feb. 7, 1922.

Application filed May 2, 1917. Serial No. 166,030.

To all whom it may concern:

Be it known that I, WILLIAM W. CROCKER, a citizen of the United States, residing at Somerville, county of Middlesex, State of 5 Massachusetts, have invented an Improvement in Metallic Windows, of which the following description, in connection with the accompanying drawing, is a specification, like characters on the drawing representing 10 like parts.

This invention relates to metallic windows and has for one of its objects to provide a novel metal window sash in which each of the bars or rails thereof is made from 15 a single piece of sheet metal folded into the required shape and in such a way that the edges of the sheet are positively locked together, and in which the bars or rails of the sash are connected at their corners 20 by an improved corner plate which simplifies the operation of manufacture and assembling.

Other objects of the invention are to improve metal window sashes and window 25 frames in the particulars hereinafter more fully set forth.

In order to give an understanding of my invention I have illustrated in the drawings a selected embodiment thereof which will 30 now be described, after which the novel features thereof will be pointed out in the appended claims.

Fig. 1 is a vertical sectional view through a window frame and window sash made in 35 accordance with my invention, the section extending from the top of the window frame to a point just below the top rail of the lower sash, parts of the sash and frame being broken out;

Fig. 2 is a section through the jamb of the window frame and the side rail of the sash;

Fig. 3 is a corner view of the sash and frame;

Fig. 4 is a perspective sectional view of a corner of the window sash showing the corner plate in operative position;

Fig. 5 is a view showing the corner plate detached from the ends of the bars of the 50 window sash;

Fig. 6 is a section on the line 6—6, Fig. 5.

In Fig. 1 which is a vertical section through a metal window frame embodying my invention, 1 indicates generally the window frame comprising the top or head portion 2, the base or sill portion (not shown)

and the sides or jambs 3. The upper sash is indicated generally at 4 and the lower sash at 5. 6 indicates the glass for the upper sash and 7 the glass for the lower 60 sash.

Each of the sashes is made of four rails or bars comprising the two side rails or stiles 8, the top rail 9 and the bottom rail 10, and these four bars or rails of each 65 sash are connected at the corners by corner plates of novel construction, thus completing the sash.

One feature of my invention relates to making each of the rails of each sash from 70 a single sheet of metal which is bent into the desired shape and is formed in such a way that the meeting edges of the sheet are positively locked together. The shape into which each of these bars or rails is 75 bent is seen best in Fig. 1. Referring, for instance, to the top rail 9 of the upper sash, this is bent into shape from a sheet thereby to form the two side faces 11, the back side 12 and the inner glass-receiving side 80 having a groove to receive the glass 6. This inner side is formed with the two suitably-shaped portions 13 and 14 which give the appearance of a molding. The portion 13 is bent inwardly at 15 to form one side 85 of a glass-receiving groove, and then is bent laterally at 16 to form the bottom of the groove. The edge of the portion 14 is also bent inwardly, as at 17, to form the other side of the glass-receiving groove. The 90 sheet from which the upper rail 9 is formed will preferably have its edges locked together at the side of the groove, and this is herein accomplished by providing the portion 17 with the laterally-extending locking flange 18 and by extending the portion 16 and bending the extension 19 thereof around the flange 18 and turning the edge 20 at right angles to the portion 16 so that it will overlie the side 17, the marginal edge of 95 100 the portion 20 being received in a groove 21 formed between the molding portion 14 and the side 17 of the groove. With this construction the two edges of the sheet will be positively locked together. The engagement of the lateral flange 18 with the portion 19 will prevent the edges from separating in a direction parallel to the plane of the glass 6, and the engagement of the marginal edge of the portion 20 in the 110 groove 21 will prevent the edges from separating in a direction transverse to the glass.

A tubular member is thus formed from a piece of sheet metal in such a way that the edge thereof cannot open up in either direction.

- 5 I will also preferably form or shape the sheet from which the rail 9 is made so as to present two ribs 22 on the upper face of the rail. All of the rails of each sash may be made in this same way, although 10 I will preferably make the upper rail 9 of the lower sash with a flat upper surface, as shown at 23. When thus made each rail of the sash is provided with a glass-receiving groove into which the edge of the 15 glass is received. The four rails of each sash are secured together at their corners by a corner plate 24 of novel construction. This corner plate comprises a body portion having two extensions 25 that are adapted to 20 overlie the side faces 11 of the adjoining bars and with two fingers 26 that are adapted to enter the hollow ribs or flanges 22. These flanges 22 are so shaped that the inner face 28 thereof is in the same plane as the face 25 11 of the rail, the outer face 27 being offset slightly and the two faces 26 and 27 are spaced apart sufficiently to receive the finger 26. The glass-receiving edge of each sash is mitered, as shown at 29. In assembling the rails, the fingers 26 of the corner plates are inserted into the space between the walls 27 and 28 of the flanges 22, and the extensions 25 thereof are arranged to overlie the faces 11 of the rails. The corner 30 plates are secured to the rails by attaching screws 30 which extend through apertures 31 and 32 formed in the corner plate and faces 11 of the rail, respectively. The corner plate is also provided with the angular extension 33 which overlies and covers the 35 joint between the mitered edges 29. The advantage of this is that the extension 33 makes a proper finish to the corner so that a finished sash is produced, even though the 40 mitered edges 29 do not fit accurately. With this construction, therefore, it is not necessary to take such pains to get an exact fit between the mitered edges 29 as would be required if the finishing extension 33 were 45 not present. It will of course be understood that the glass is to be placed in the glass receiving grooves as the rails of the sash are being assembled. A corner plate of the 50 above nature would be used on both sides 55 of the sash at each corner, thus requiring eight corner plates for each sash. If desired the two corner plates at each corner may be connected by the bridge piece 44 as seen in Fig. 6.
- 60 The sides, top and bottom of the window frame are also made of sheet metal bent into the proper shape. The top or head 2 of the window frame is formed so as to present the two guiding ribs 34 between which the 65 flanges 22 of the top rail of the upper sash

are received. The jamb 3 of the window frame is bent to present the outwardly-extending rib 34 and the inwardly-extending grooves 35 and 36. These grooves receive parting strips 37 which are made of sheet 70 metal. Each parting strip is made from a strip of sheet metal which is bent back on itself centrally and one edge 38 of which is received in the groove 35 or 36, and the other edge 39 of which is bent back parallel 75 to the body thereby to form with the body a groove 40. The groove 40 of each parting strip is adapted to receive and form a guide for one of the flanges 22 of a sash.

The sides and top and bottom of the window frame are connected together at the corners by corner plates 43 which have the same construction as the corner plates 24.

I claim:

1. A window sash comprising connected side and top and bottom rails, each rail being formed from a single sheet of metal bent into the required shape to form a glass-receiving groove, both sides of which are formed from bends in said sheet metal, the 90 meeting edges of each sheet being situated at one side of the groove and being positively interlocked against separating movement in either a direction parallel to the plane of the sash or in a direction transverse 95 to said plane.

2. A window sash comprising connected side and top and bottom rails, each rail being formed from a single sheet of metal bent into the required shape to form a glass- 100 receiving groove, both sides of which are formed by the sheet metal, the meeting edges of each sheet being situated at the side of the groove and being positively interlocked against separating movement in either one 105 of two directions at right angles to each other.

3. A metal window sash comprising side, top and bottom rails, each formed from a sheet of metal bent into the desired shape, and corner plates for securing said rails together, 110 each corner plate having an extension overlying the outer face of each rail, and a finger which overlies the inner face, and means securing the corner plate to the rail. 115

4. A metal sash comprising side, top and bottom rails, each being formed of a piece of sheet metal bent into the desired shape and provided with a glass-receiving groove, 120 each rail being mitered at both ends on its glass-receiving edge, and corner plates for connecting said rails, each corner plate having a downwardly and inwardly-directed extension which is situated on the outside of and overlies the meeting mitered edges of 125 two rails.

In testimony whereof, I have signed my name to this specification.

WILLIAM W. CROCKER.
